COOLING SYSTEM FOR INTERNAL-COMBUSTION ENGINES

John C. Slonberger, Dallas, Tex., assignor to The Continental Supply Company, Dallas, Tex., a corporation of Delaware

Application December 13, 1947, Serial No. 791,485

12 Claims. (Cl. 123—41.15)

1

This invention relates to new and useful improvements in cooling systems for internal combustion engines.

One object of the invention is to provide a cooling system for internal combustion engines having improved means for permitting the addition of water, or other coolant, to the cooling system while the engine is running or in operation.

An important object of the invention is to provide an improved filling means for the cooling systems of internal combustion engines which provides a relatively accurate estimate of the coolant level within the engine, and wherein provision is made for preventing the inherent turbulence of the coolant in such an engine from being reflected in the level indicating means.

A further object of the invention is to provide an improved means for adding a coolant, such as water, to the cooling system of an internal combustion engine which reduces to a substantial degree the loss of coolant or anti-freeze solution by excessive evaporation through the means by which the coolant is added to the cooling system.

A particular object of the invention is to provide an improved means for adding a coolant to the cooling system of an internal combustion engine wherein said cooling system is of the convection circulation type, said means facilitating the quick and easy determination of the coolant level within the system and the maintenance of said level within the maximum and minimum limits desired.

A construction designed to carry out the invention will be hereinafter described together with other features of the invention.

The invention will be more readily understood from a reading of the following specification and by reference to the accompanying drawing, wherein an example of the invention is shown, and wherein:

Fig. 1 is a perspective view of an internal combustion engine having incorporated therein a cooling system constructed in accordance with this invention,

Fig. 2 is an enlarged, side elevation of the coolant addition means, and

Fig. 3 is a vertical, sectional view showing the means of circulation between the water jacket of the engine and the water tank carried thereby.

In the drawing, the numeral 10 designates an internal combustion engine which may be of any desired type or structure in which a convection circulation cooling system is employed. The engine illustrated is of the horizontal type, and it is customary to use what might be called a static

2

cooling system in such engines. The engine is provided with the usual water jacket 11 surrounding the cylinder or cylinders (not shown); and a coolant such as water is maintained in said jacket. However, the coolant is not circulated under pressure but remains in a static body surrounding or enclosing the heated portions of the engine. As the engine generates heat in running, the coolant is heated and circulates by convection through the jacket and normally reaches its boiling point after a considerable period of operation of the engine.

As a part of the cooling system, a flat tank 12 is secured on top of the jacket 11 and communicates therewith by means of an opening 13 in the bottom of the tank 12 and which communicates with a corresponding opening 14 in the upper side of the jacket 11. In this manner, water or any other suitable coolant may be supplied through the tank to the jacket wherein it may circulate about the heated portions of the engine. A suitable vented radiator 15 is connected with and supported on the tank and is provided with a fan (not shown) enclosed in a suitable guard 16 for drawing air through the radiator and cooling the same. The vapors evolved by the coolant in the jacket 11 pass upwardly into the radiator 15, wherein the same are condensed and returned to the cooling jacket.

The radiator 15 may be of any suitable or desirable construction and may be vented in any desired fashion. Normally, the radiator will be of the vertical tube type and is provided at its lower end with an open space *a* communicating with the tank 12. A transverse partition *b* in the radiator carries the lower ends of upwardly extending radiator tubes *c*, and normally, a second communicating space (not shown) is provided at the upper end of the radiator, and the bores of the radiator tubes *c* communicate therewith. For venting the radiator, the lower end of one of the tubes *c* is closed, this tube being designated as tube *d*, and is provided with the plug *e* in its lower end. A small opening *f* is drilled through the wall of the tube *d*, and hence, the radiator is vented from the upper communicating space, downwardly through the tube *d* and outwardly through the opening *f*.

In this type of engine, steam or vapor cooling is ordinarily employed since the engine is not harmed by operating at elevated temperatures so long as certain maximums are not exceeded. Such engines are designed to operate at temperatures near or at the boiling point of water, or other coolant utilized, so that it is quite cus-

tomary for the coolant to be at a substantially constant boil during operation of the engine.

While the engine is not adversely affected by these elevated operating temperatures so long as an adequate quantity of coolant is present in the jacket 11, a number of difficulties inherently exist in the operation of such a cooling system. One difficulty has been the determination and maintenance of a proper coolant level within the system. Because of the boiling and the consequent turbulence of the coolant, there is considerable bubbling and agitation within the cooling jacket and the accurate determination of the coolant level is rendered well nigh impossible. The determination of this coolant level is important since, if it becomes too low, the engine may overheat because of inadequacy of the quantity of coolant present. At the same time, if too much coolant is added, the boiling liquid may be thrown upwardly through the radiator passages or tubes and result in priming of the radiator. When the latter occurs, considerable quantities of the coolant may be tied up in the radiator or entrapped therein, and in addition, portions of the coolant may be blown from the vent of said radiator by vapor pressure, and thus lost.

In view of these difficulties, it has been common practice in the past to determine the coolant level within the engine after the latter has been stopped and boiling of the coolant has ceased. Obviously, it is unsatisfactory and impractical to stop the engine each time it is desired to check the coolant level. This is especially true since engines of this type may be expected to operate for long periods of time without stopping, or may be employed in installations where the engine must run substantially continuously.

The present invention overcomes the difficulties recited by attaching to the outside of the tank 12 an upright cup or receptacle 17 having a loosely fitting lid 18 which, while held closed by a spring-type hinge 19, is nevertheless non-sealing. A Z-shaped bracket 17' is carried by the engine and supports the cup at the same elevation as the normal coolant level in the engine. The cup has a reduced, depending, tubular portion 20 into the bottom of which an elbow 21 (preferably 45°) is fastened. An elbow 22 is screwed into the side of the jacket 11 below or substantially in the plane of the longitudinal axis of the engine piston (not shown) which is substantially the medial portion of said jacket. A U-shaped surge tube 23 has one leg suitably connected with the elbow 22 and the upper end of the opposite leg of the tube is bent to form an inclined extension 24 which is suitably connected with the elbow 21. It is obvious that the coolant level in the jacket 11 and tank 12 will be the same as the coolant level in the cup 17, since both the radiator and said cup are vented to the atmosphere. The cup is of such depth that its bottom corresponds to the minimum desirable level of the coolant in the jacket which is deemed safe for operation, while the top of the cup is at such an elevation that it corresponds to the highest coolant level that may be maintained without causing objectional surging of steam or vapor in the radiator tubes, along with the consequent priming of said radiator.

It will be apparent that so long as the coolant is present in the cup, the engine may be safely operated insofar as its cooling system is

concerned. An abnormal rise in the coolant level, due to expansion or displacement by steam or vapor, above the level of the top of the cup or by the addition of excessive amounts of coolant to the cooling system, will cause the coolant to overflow the cup since the lid 18 is not sealed. In a similar fashion, the operator of the engine may examine the coolant level by raising the lid 18 without shutting off the engine, or may add additional coolant when the coolant level reaches the bottom of the cup. Because of the inertia of the column of liquid in the tube 23, variations in pressure due to the turbulence or boiling of the coolant will not cause objectionable movement of liquid in the cup. One purpose of forming the tube in a U-shape is to prevent thermo-syphonic circulation of the coolant in the jacket and the cup 17. Since no return conductor is available and since the tube 23 is of relatively small diameter, such thermo-syphonic circulation will not occur.

Since water is normally used as the coolant liquid for this type of engine and since water is a relatively poor conductor of heat, such water, or other coolant, as remains in the cup will be comparatively cool, thus preventing loss by excessive evaporation from the cup, or the loss of anti-freeze solution when the same is used. Coolant may be added by pouring the same into the cup when the engine is running or when the engine is idle. The cup and the radiator being vented to the atmosphere, the vapor pressure in the cooling system never exceeds that of the atmosphere, and the liquid levels in the cooling jacket and in the cup remain substantially the same.

In this manner, since the turbulence of the coolant in the jacket 11 is not communicated to the coolant within the cup 17, said coolant will seek and maintain a substantially constant and steady level representing the true level of the coolant within the jacket 11. The operator of the engine may determine by a glance within the cup 17 whether such level is within the described limits and thus be able to maintain the cooling system of the engine filled to the proper operating level. At the same time, coolant may be added at any time that such becomes necessary or desirable, by mere pouring into the cup 17. The addition of excessive quantities of coolant is automatically negated by the overflowing of the excessive amount from the upper end of the cup 17.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A cooling system for internal combustion engines including, a cooling jacket vented to the atmosphere, a filling receptacle vented to the atmosphere and having an open bore, and a U-tube connecting the receptacle and the jacket and forming an unobstructed passage between the bore of the receptacle and the jacket.

2. A cooling system for internal combustion engines including, a cooling jacket vented to the atmosphere, a filling receptacle vented to the atmosphere and having an open bore, and a U-tube of restricted diameter connecting the receptacle and the jacket and forming an unobstructed pas-

sage between the bore of the receptacle and the jacket.

3. A cooling system for internal combustion engines including, a cooling jacket vented to the atmosphere, a filling receptacle vented to the atmosphere and disposed in the horizontal plane of the normal coolant level within the cooling jacket, said filling receptacle having an open bore and a U-tube connecting the receptacle and the jacket and forming an unobstructed passage between the bore of the receptacle and the jacket.

4. A cooling system for internal combustion engines including, a cooling jacket vented to the atmosphere, a filling receptacle vented to the atmosphere and having an open bore, a hinged lid for the receptacle, and a U-shaped tube connecting the receptacle and the jacket and forming an unobstructed passage between the bore of the receptacle and the jacket.

5. A cooling system for internal combustion engines including, a cooling jacket vented to the atmosphere, a filling receptacle vented to the atmosphere and having an open bore, and a U-shaped tube connecting the lower end of the receptacle and the jacket and forming an unobstructed passage between the bore of the receptacle and the jacket.

6. A cooling system for internal combustion engines including, a cooling jacket vented to the atmosphere, a filling receptacle vented to the atmosphere and having an open bore, and a U-shaped tube connecting the receptacle and a point in the jacket below the normal coolant level therein and forming an unobstructed passage between the bore of the receptacle and the jacket.

7. A cooling system for internal combustion engines including, a cooling jacket vented to the atmosphere, a filling receptacle vented to the atmosphere and having an open bore, and a U-shaped tube connected between the lower end of the receptacle and a point in the jacket below the normal coolant level therein and forming an unobstructed passage between the bore of the receptacle and the jacket.

8. A cooling system for internal combustion engines including, a cooling jacket vented to the atmosphere having a normal coolant level therein, an open top cup having an open bore and having its upper end above the elevation of said normal coolant level, and a U-tube connecting the jacket and the cup and forming an unobstructed passage between the bore of the receptacle and the cup.

9. A cooling system for internal combustion engines including, a cooling jacket vented to the atmosphere having a normal coolant level there-

in, an open top cup having its upper end above the elevation of said normal coolant level, and a U-tube communicating between the cup and a point in the jacket below the normal coolant level.

10. A cooling system for internal combustion engines including, a cooling jacket vented to the atmosphere having a normal coolant level therein, an open top cup having its upper end above the elevation of said normal coolant level, the lower end of the cup being below said level, a spring-pressed lid for the cup, and a U-shaped tube communicating between the cup and the jacket, one leg of the tube being longer than the other and connected into the bottom of the cup, the shorter leg being connected into the jacket at a point substantially below the normal coolant level.

11. A cooling system for internal combustion engines including, an engine cooling jacket vented to the atmosphere, an elevated coolant receptacle connected with the engine radiator and jacket, a liquid level indicating and filling container located opposite the receptacle, and a connection between the container and the jacket including a surge trap.

12. As a sub-combination in an internal combustion engine, means for adding water to said engine, said means including a U-shaped conductor having one end connected to the water jacket of the engine, and an enlarged section at the opposite end of said conductor, there being an open continuous passage through the conductor and the enlarged section at the opposite end of said conductor.
